FLARE HOUSING WITH SIMULTANEOUSLY
OPERATED WICK HOOD CAPPING MEANS
ON CLOSUREWilliam O. Pajuoja, Deer River, Minn., assignor
of one-half to Charles A. Voigt, Deer River,
Minn.

Application June 6, 1950, Serial No. 166,437

4 Claims. (Cl. 206—1)

1

The present invention relates to improvements in mounting devices for vehicle road flares and more particularly to the type of mounting device wherein means are provided for uncapping each of a plurality of flares simultaneously.

An object of the present invention is to provide an improved device for supporting a plurality of flares on a truck and wherein each of the flares is uncapped by rotation of a handle means mounted on the closure of the supporting device.

A further object of the present invention is to provide an improved supporting device for vehicle flares wherein the flare housing is provided with means for storing a plurality of signal flags for use during the day time.

Another object of the present invention is to provide a novel actuating means for simultaneously uncapping the plurality of vehicle flares wherein means is provided for locking said first mentioned means in an inoperative position.

This invention also has for its objects to provide a device for supporting a plurality of self-uncapping road flares on a vehicle that is convenient in use, easily installed on a truck and easily disconnected therefrom, economical of manufacture, relatively simple and of general superiority.

Various other objects and advantages will be apparent from the detailed description to follow.

The means by which the objects of the present invention are accomplished include a housing having an open side, a closure for the open side, a plurality of shelves secured to a side wall of the housing for supporting individual flares, each of the flares having a spring urged wick hood, guide means mounted on the closure, a side member reciprocably mounted on the guide means, a plurality of cap straps secured to the side member in spaced relation and adapted to have their outer ends in juxtaposition with each of the wick hoods, a cap secured to the outer end of each of the cap straps and engageable with each of the wick hoods for retention thereof, actuating means for selectively engaging and disengaging the caps from the wick hoods, and locking means for securing the actuating means in one position.

The best form in which I have contemplated applying my invention is illustrated in the accompanying drawings, wherein:

Figure 1 is a side elevational view showing the device mounted on a truck with parts of the truck broken away;

Figure 2 is a vertical transverse sectional view

taken substantially along the plane of line 2—2 of Figure 1;

Figure 3 is a vertical transverse sectional view through the housing showing the flare caps in partially raised position with one of the flares shown in section;

Figure 4 is a horizontal transverse sectional view taken substantially along the plane of line 4—4 of Figure 3;

Figure 5 is an elevational view of the present invention showing the housing with a plurality of flares therein and the closure in open position; and,

Figure 6 is a side elevational view of a portion of the present invention as seen from the plane of line 6—6 of Figure 3.

Referring more particularly to the drawings, wherein like numerals designate like parts throughout, numeral 10 designates generally a vehicle upon which the present invention is to be mounted. As seen in Figure 1, the self uncapping flare box 12 is secured to the vehicle 10 on the door panel at 14.

The self uncapping road flare box 12 comprises a housing 16 having upper and lower walls 18 and 20, side walls 22, 24 and 26, a vertical strap 28, and a plurality of shelves 30 secured to side walls 22 and 26 and the vertical strap 28. Each of the shelves 30 is provided with upstanding flanges 32 at its inner edges for retention of the vehicle flares 34. Any conventional means such as weld may be employed to secure the shelves 30 in the desired spaced relation in the housing 16.

The housing 16 is also provided with an arcuately bent longitudinally extending partition wall 36 which is secured to the side walls 24 and 26 adjacent one corner of the housing. The partition wall 36 and the adjoining side walls provide an enclosure for storing a plurality of signal flags for use during the daytime. A sector closure element 38 is pivotally mounted at 40 on the housing 16 for pivoting movement from open to closed position, covering the opening at the bottom of the enclosure for the flags. The closure element 38 is provided with a handle projection 42 adjacent its outer periphery.

The closure 44 is hingedly attached to the housing 16 by means of the hinges 46 and is secured in closed relation to the housing 16 by means of the latch bracket 48 on the housing 16 and the latching element 50 of the closure 44. The closure 44 is also provided with a plurality of bolts 52 and nuts 53 secured to the wall 54

whereby the entire device may be secured to the door panel of the vehicle 10.

The device is provided with an actuating handle 56 which is rotatably mounted with respect to the wall 54 and is adapted to be positioned on the inner side of the cab of the vehicle 10 for manipulation by the driver.

On the inner face of the wall 54, a pair of guide bars 58 are fixedly secured at 60. Also mounted on the inner face of the wall 54 is a sleeve bearing bracket 62 which is secured by means of screws 65. Rotatably mounted in the bearing bracket 62 is a handle shaft 64 having a non-circular end engageable by the handle member 56 whereby the handle member is slidably on the handle shaft 64 but rotates therewith. The outer end of the handle shaft 64 is provided with a disc spring retainer 66 against which a spring 68 has one end abutting for normally urging the handle 56 in a direction of the wall 54. The wall 54 is also provided with a lock pin 70 which is engageable in an aperture 72 provided in the handle 56 to prevent rotation of the handle except when desired.

The inner end of the handle shaft 64 has secured thereto an arm 74 and pin 76 forming a crank. The crank 74—76 is provided with a connecting rod 78 which is rotatably mounted thereon at pin 80. A slide bar 82 is connected to the connecting rod 78 by means of pin 84 which is rotatably received in an aperture at the outer end of the connecting rod 78. The slide bar 82 is provided with a plurality of longitudinal slots 86 which are adapted to receive the ends of the guide rods 58.

The slide member 82 is provided with a plurality of transversely extending and vertically spaced cap straps 88 which are rigidly secured thereto by means of weld or the like at 90. Each of the cap straps 88 is provided with a bevelled cap 92 provided with a sealing ring 94.

Each of the plurality of vehicle flares 34 is provided with a downwardly extending beveled flared neck 95 in which is slidably received the wick hood 96. The wick hood 96 is resiliently urged outwardly by means of a spring 98 and is engageable with the cap 92.

It is believed that from the foregoing description taken in conjunction with the drawings, the operation of the present invention will be readily apparent to one skilled in the art. When the driver of the vehicle desires to use the flares, he merely manipulates the actuating handle 56, urging it against the spring 68 and out of engagement with the lock pin 70. He then may rotate the handle 56 and handle shaft 64 causing the rotation of the crank and reciprocation of the slide bar 82 by means of the connecting rod. The reciprocation of the slide member lifts the cap 92 which is sealingly engaged in the flared neck 95, permitting the wick hood to rise. The truck driver may then get out of the cab of the vehicle and unlatch the housing 16 from the closure 44, pivoting on the hinge means 46, and then he may remove the flares for positioning on the roadway as desired.

Some changes may be made in the construction and arrangement of the parts of my device without departing from the real spirit and purpose of my invention.

Having described the invention, what is claimed as new is:

1. A device for supporting a plurality of self uncapping road flares on a vehicle comprising: A housing having an open side, a closure for

said open side, a plurality of shelves secured to a side wall of said housing for supporting individual flares of the type having spring urged wick hoods, vertical guide means mounted on said closure, a slide member reciprocably mounted on said guide means, a plurality of cap straps fixedly secured to said slide member in spaced relation to each other and having their outer ends overlying said shelves in vertically spaced relation thereto, a cap secured to said outer end of each of said cap straps for engaging each of such wick hoods for retention thereof, and actuating means for simultaneously displacing said caps from such wick hoods.

2. A device for supporting a plurality of self uncapping road flares on a vehicle comprising: A housing having an open side, a closure for said open side, a plurality of shelves secured to a side wall of said housing for supporting individual flares of the type having spring urged wick hoods, vertical guide means mounted on said closure, a slide member reciprocably mounted on said guide means, a plurality of cap straps fixedly secured to said slide member in spaced relation to each other and having their outer ends overlying said shelves in vertically spaced relation thereto, a cap secured to said outer end of each of said cap straps for engaging each of such wick hoods for retention thereof, and actuating means for simultaneously displacing said caps from such wick hoods, said last named means mounted on said closure and connected to said slide member, and locking means for securing said last named means in one position.

3. A device for supporting a plurality of self uncapping road flares on a vehicle comprising: A housing having an open side, a closure for said open side, a plurality of shelves secured to a side wall of said housing for supporting individual flares of the type having spring urged wick hoods, vertical guide means mounted on said closure, a slide member reciprocably mounted on said guide means, a plurality of cap straps fixedly secured to said slide member in spaced relation to each other and having their outer ends overlying said shelves in vertically spaced relation thereto, a cap secured to said outer end of each of said cap straps for engaging each of such wick hoods for retention thereof, and actuating means for simultaneously displacing said caps from such wick hoods, said last named means including a handle mounted on said closure, a crank fixed to the inner end of said closure, a connecting rod rotatably secured to said crank and to a connecting pin on said slide member whereby rotation of said handle imparts reciprocation to said slide bar.

4. A device for supporting a plurality of self uncapping road flares on a vehicle comprising: A housing having an open side, a closure for said open side, a plurality of shelves secured to a side wall of said housing for supporting individual flares of the type having spring urged wick hoods, vertical guide means mounted on said closure, a slide member reciprocably mounted on said guide means, a plurality of cap straps fixedly secured to said slide member in spaced relation to each other and having their outer ends overlying said shelves in vertically spaced relation thereto, a cap secured to said outer end of each of said cap straps for engaging each of such wick hoods for retention thereof, and actuating means for simultaneously displacing said caps from such wick hoods, said last named means mounted on

said closure and connected to said slide member, and locking means for securing said last named means in one position, said locking means including a lock pin mounted on said closure, an aperture in said actuating means into which said lock pin is projectable, and means for normally urging said actuating means to locked position.

WILLIAM O. PAJUOJA.
